UNITED STATES PATENT OFFICE.

LAURENCE D. HARRISON, OF PHOENIX, ARIZONA.

TELEPHONE-CALL REGISTER.

1,367,383.

Specification of Letters Patent.

Patented Feb. 1, 1921.

Application filed April 30, 1917. Serial No. 165,421.

To all whom it may concern:

Be it known that I, LAURENCE D. HARRISON, a citizen of the United States, and resident of Phoenix, in the county of Maricopa and State of Arizona, have invented certain new and useful Improvements in Telephone-Call Registers, of which the following is a specification.

The present invention has reference, generally, to telephony and the invention relates more particularly to an improved registering apparatus therefor.

The invention has for its dominant object to provide a registering apparatus for telephones whereby a party calling a second party and not receiving an answer can register the number of his phone or the phone on which he desires to be called at the called station, thereby, providing a memorandum for the called party upon his return.

It is also an object of the invention to provide means for automatically operating the number registering means arranged at the called station, whereby, a desired number may be selected and printed on a suitable strip arranged adjacent thereto.

A further object of the invention is to provide means for returning the registering means to normal position subsequent to a printing or registering operation.

Further, it is yet another object of the invention to provide means for automatically rendering the registering device operative after the bell at the called station has been rung a predetermined number of times.

Other independent objects are to provide features of construction of the apparatus which tend toward the attainment of the above aims irrespective of the relation in which they are used.

Other objects will be in part obvious and in part pointed out hereinafter.

The invention accordingly consists in the features of construction, combination of elements and arrangement of parts which will be exemplified in the construction herein-after set forth and the scope of the application of which will be indicated in the following claims.

50 In the drawings, wherein is shown one of various possible embodiments of my invention,

Figure 1 is a vertical longitudinal section through the registering apparatus;

55 Fig. 2 is a horizontal longitudinal section of the parts shown in Fig. 1;

Fig. 3 is a transverse section in detail through the type carrying wheel;

Fig. 4 is a side elevation partly in section, showing the automatic circuit closing means whereby the registering apparatus is rendered active.

Fig. 5 is a diagrammatic view showing the arrangement of the electrical circuit for operating the various parts of the apparatus.

Fig. 6 is an edge view partly in section, of portion of the parts shown in Fig. 5.

Referring now more specifically to the drawings and in connection with which like reference characters will refer to corresponding parts throughout the several views, there is provided a casing or housing designated in its entirety by the numeral 1, which housing serves as means for containing the various parts of the call registering apparatus and, of course, is located at the called station.

Rotatably mounted upon a stub shaft 2 which is in turn supported upon a bracket 3, is a type carrying wheel 4 including inner and outer rims, which rims constitute the peripheries of disk like elements 5 and 6. Slidably arranged in suitable openings formed in the inner and outer rims are a plurality of type carrying rods or plungers 7, which plungers are normally held in their inoperative positions by means of coiled springs 8 which are arranged about the intermediate portions thereof and having bearing upon the adjacent faces of the said rims. Type representing the various numerals ranging from 0 to 9 are carried by the said plungers 7 and are adapted, at times, to be impressed upon a suitable recording strip which will be hereinafter more fully described. To normally maintain the type carrying wheel 4 in its inoperative position, a spring 9 is arranged about the outer extremity of the stub shaft 2 and has engagement therewith, the said spring being supported upon the stub shaft by means of an angular bracket 10. A ratchet wheel 11 is keyed to a portion of the stub shaft 2 and serves as means for locking the type carrying wheel 4 in selected position.

Bearing brackets 12 are fixedly secured to a portion of the housing bottom and rotatably support therebetween a recording roller 13, while directly above the said recording roller a rubber feeding roller 14 is also rotatably supported within suitable brackets, this roller being mounted upon a shaft 15 carrying upon one portion thereof

a ratchet wheel 16. The paper strip from the recording roller 13 is passed upwardly over the feeding roller and from there through a diagonally disposed way or slot 5 formed in the housing casing into view of the user. Spools 18 are rotatably supported upon suitable bearings and have wound thereabout a carbon ribbon 19, the intermediate portion of which is arranged over that 10 portion of the feeding roller 14 as adjacent the particular type selected upon the type carrying wheel.

A magnet 20 is supported within the housing upon a bracket 21 and has arranged adjacent its respective pole an armature plate 22 carried upon a rod 23 slidably mounted upon a substantially U-shaped bracket 24 and normally maintained in spaced relation from the said magnet pole by means of a 20 coil spring 25. Pivotedly carried upon the outer extremity of the rod 23 is a pawl 26, the rear extremity of which is offset as at 27 to provide an efficient armature plate.

Another magnet 28 is supported within 25 the bracket 21 and has its pole so arranged as to attract the armature plate 27 of the pawl 26 when energized, while below the same a second armature plate 29 formed upon a pawl 30 which is pivotally supported 30 in bearings 31 is arranged. A contractile coil spring 32 having engagement with the pawls 26 and 30 serve as means for normally maintaining the same in engagement with the ratchet wheel 11, thereby locking the 35 type carrying wheel. Contact plates 33 and 34 are arranged directly beneath the magnet 28, the latter being movable with relation to the former whereby when engaged by the armature plate 29 a permanent circuit will 40 be closed through its respective magnet 28.

Pivotedly supported upon a bracket 35 is a hammer 36, the lower extremity of which is arranged adjacent the pole of a magnet 37 and is adapted to be attracted thereby, 45 at times, in order that the particular type which has been moved to selected positions by the carrying wheel 4 may be engaged and forced into contact with the carbon ribbon 19. A coil spring 38 having engagement 50 with the bracket 35 and the lower portion of the hammer 36 serves as means for normally maintaining the same in spaced relation from the various type carrying plungers and the pole of the magnets 37.

55 Circuit closing means comprising a substantially U-shaped element having weighted extremities is pivotally supported upon a bracket 39 secured to a portion of the housing bottom and serves for a purpose which 60 will be subsequently apparent.

As means for automatically advancing or 65 rotating the feeding wheel 14 there is provided a magnet 40 having an armature 41, which armature is carried upon a slidably L-shaped operating arm 42 pivotally mount-

ed on the shaft 15 and carrying thereon a pivotal pawl 43 engageable with the ratchet wheel 16. A contractile coiled spring 44 which is engaged with a portion of the arm 42 and the housing top serves as means for 70 normally maintaining the former in its uppermost position. Upon the energizing of the magnet 40, it is evident that the plates 41 will be brought into engagement with the magnet pole and as a consequence the ratchet 75 wheel 16, together with feed wheels 14 will be automatically advanced one step. Thus, spacing of the characters stamped upon the recording tape or strip is permitted.

Referring now to the automatic circuit 80 closing means for the registering apparatus, which means is arranged at the calling station, there is provided a bracket 45 carrying a shaft 46 on which a ratchet wheel 47 is mounted. A tripping element 48 having a 85 plurality of beveled lugs 48' formed upon its peripheral surface is also mounted on the shaft 46 and is adapted to rotate with the ratchet wheel 47. Spring contact arms 49 are secured to a suitable base adjacent the 90 bracket 45 and project upwardly into proximity of the tripping element 48, the adjacent contact arm being arranged in the path of travel of the beveled lugs 48' as shown to advantage in Fig. 4. Other spring contact 95 arms 50 are carried by one of the contact arms 49 and are so arranged as to permit engagement of the beveled lugs 48' with the lowermost thereof. A magnet 51 is provided and serves to attract the plate 52 carried upon the adjacent end of a rod 53, which rod has secured to its outer end a 100 slidable pawl 54. To normally maintain the armature plate and pawl in retracted positions a coil spring 55 is engaged with an 105 extremity of the rod 53 and with a bracket 56 fixedly supported upon the base of the circuit closing device.

To permit the turning of the shaft 15 by hand, a hand wheel 15' may be and preferably is arranged upon the outer end thereof which projects beyond the housing 1.

Having reference now to the wiring of the various magnets of the registering apparatus, *a* indicates a source of electrical 115 energy having conductors *b* extending therefrom into engagement with the contact terminals of the magnets 20, one of the said conductors having spring contact arms *b'* interposed therein and adapted to be engaged by a cam 57 arranged upon the usual number selecting dial 58 commonly used in conjunction with intercommunicating telephone systems, such dial or other kindred devices being located at the calling station. Other conductors *c* are engaged with the opposite poles of the source of energy *a* and with the contact terminals of the magnets 37, certain of the said conductors having 120 circuit closing means *d* interposed there- 125

in and operable by means of a lug 59 carried upon the periphery of the dial 58. From one of the conductors *c* a branch conductor *e* extends into engagement with one of the contact terminals of the magnet 40 while the other contact terminal thereof is engaged by a conductor *e'* which in turn extends into engagement with the lower portion of the hammer 36. The conductor *e* has connection with the adjacent side of the V-shaped circuit closing element 39' while a conductor *f* is engaged with the opposite side of the hammer 36 and extends from the same into engagement with one contact terminal of the magnet 28, the remaining terminal of the said magnet being connected with a conductor *g* extending through spring circuit closing arms *h* into engagement with the return side of the circuit formed by the several conductors *c*. Other spring circuit closing arms *i* are arranged adjacent the magnets 28 and are adapted to be closed upon movement of its armature 27, the same being connected with the magnet 25 by means of branches *j* and *j'*, the former being connected with one of the conductors *e* while the latter is connected with the conductor *f*. Conductors *k* are extended from the conductors *e* and *e'* into engagement with the circuit closing means of the telephone and upon removal of the receiver from its supporting hook will serve to energize the magnet 40 for a purpose which will be subsequently obvious. A finger 60 is carried upon one side of the outer rim of the type carrying wheel 4 and is adapted to be engaged with the longer of the spring circuit closing arms *h* at times to discontinue the flow of energy through the magnets 28. The automatic circuit closing device shown in the Fig. 4 has the magnet 51 thereof engaged with a plurality of shunt wires *l* extending from the bell ringing circuits *m* and has the spring arms 49 interposed in one of the conductors *d* while the arms 50 are interposed in one of the conductors of the bell ringing circuit *m* of the telephone system.

In operation when the bell at the call station has been rung for a predetermined number of times one of the beveled lugs 48 carried by the tripping element 48 will engage the adjacent spring arms 49 thereby closing the registering circuit and a second 55 of the beveled lugs will engage one of the spring arms 50, thereby breaking the bell ringing circuit. At this time, the party calling is now in connection with the register of the called party and having received no reply 60 to his call may proceed to register the number of his phone or the phone upon which he desires to be called by operating the dial of the phone to register the number thereof upon the supporting apparatus of the called station. During the registering of the number 65 of the calling phone upon the recording means arranged at the called station the cam 57 arranged upon the dial 58 will make and break a circuit through the conductors *b* according to the particular number turned upon the dial, thereby transmitting electrical impulses to the magnet 20. Each time a circuit is completed through the magnet 20, the armature plate 22 and the rod 23 are drawn into engagement therewith, thereby 70 moving the type carrying wheel 4 into a position whereat the corresponding number upon one of the type carrying plungers will be alined with the recording strip arranged over the feeding roller 14. When the circuit is broken during the turning of the cam the rod 23 will be returned to its normal position by means of the spring 25 engaged therewith. When the number of the calling station has been obtained upon the type carrying wheel 4 the dial 58 is then returned to its normal or inoperative position, whereupon the lugs 59 carried thereby will engage the circuit closing means *d* thus closing a circuit through the magnets 37 and 75 drawing the armature portion of the pivoted hammer 36 into engagement therewith. Such movement will cause the hammer 36 to strike the alined type carrying plunger, impressing the characters arranged thereon upon the recording strip whereupon the said plunger will be immediately returned to its normal position by means of the spring 8 arranged thereabout. As the magnet 37 draws the lower portion of the hammer 36 thereto one side of the V-shaped circuit closing element 39 is engaged therewith and hence, upon the return of the hammer to its normal position, the same will engage the remaining side of the said circuit closing 85 element which is connected to the conductor *e*, thus, for an instant closing a circuit through the magnet 28 whereupon the armatures 27 and 29 are drawn into engagement therewith and the ratchet wheel 11 arranged upon the shaft 2 is disengaged by the pawls 26 and 30 and the type carrying wheel permitted to return to its normal position by means of the spring 9. As the armature 29 is drawn into engagement with the magnets, the contact members 33 and 34 will be engaged and as a consequence a permanent circuit is established through the magnet 28, thereby maintaining the pawls 26 and 30 out of engagement with the said ratchet wheel 11 until the type carrying wheel has returned to its normal or inoperative position whereat it is ready to receive the next number to be registered thereby. Just before the type carrying wheel 4 is returned to its normal position a finger 60 carried thereby will engage the longer of the spring circuit closing arms *h*, thereby breaking the circuit through the magnets 28 and allowing the pawls 26 and 30 to reengage their respective ratchet 100 105 110 115 120 125 130

wheels 11. Due to the engagement of the branch conductors *k* with the conductors *e* and *e'*, it will be understood that the feeding roller 14 will be advanced one step, the sheet correspondingly advanced and the record made while the receiver is on the hook, thereby advancing the recording case and causing the number printed thereon to be spaced from the following number. Thus, 10 the party at the called station upon his return may readily read the various numbers of those stations to be called by him.

Although I have in the above description referred to the improved registering apparatus as being applicable to the intercommunicating type of telephone system, it will be evident to persons skilled in the art that the invention may be used in conjunction with various other types of systems, such as 20 conditions or preference may dictate.

As many changes could be made in the above construction and many apparently widely different embodiments of this invention could be made without departing from 25 the scope thereof, it is intended that all matter contained in the above description or shown in the accompanying drawings shall be interpreted as illustrative and not in a limiting sense. It is also to be understood 30 that the language used in the following claims is intended to cover all of the generic and specific features of the invention herein described and all statements of the scope of the invention, which, as a matter of language 35 might be said to fall therebetween.

I claim:

1. In a registering apparatus, a wheel mounted for rotation, type carrying plungers arranged radially of said wheel, a recording strip movable relative to said wheel and adapted to receive the imprint from 40 said plungers, a ratchet rotatable with the wheel and having teeth corresponding to the plungers thereof, an operating pawl engageable with said ratchet, electrically operated means for moving said pawl to rotate said ratchet and the wheel connected thereto, electrically operated means for tripping said pawl, and electrically operated means for actuating said type bearing 45 plungers.

2. In a registering apparatus, a rotatable wheel, a plurality of type carrying plungers operating radially of the wheel, a recording 50 strip movable relative to the wheel, elec-

trically operative means for rotating the wheel to locate the plungers selectively in position to engage the strip, means for locking the wheel subsequent to the rotation thereof, a hammer device arranged to strike 60 the plunger which for the time being is in position to engage the strip and electrically operated means for advancing the recording strip.

3. In a registering apparatus, a wheel including spaced inner and outer rims, spring pressed type carrying plungers arranged on the type carrying wheel, a movable tape arranged in proximity of one side of the wheel, magnetically operated means 70 for rotating the wheel to selectively locate the plungers to engage the tape, a hammer device including a vibrating member and an extended arm, and electrically operated means for actuating the hammer device and 75 advancing the movable tape.

4. In a call registering device, a casing, a rotatable supporting element in said casing, a plurality of type carrying members slidably arranged relative to said element, a recording strip arranged in proximity to the supporting element, means for rotating the supporting element to align a selected type carrying member with said strip, a hammer device including a vibrating member 85 and an extended arm, and electrically operated means for actuating the hammer device and advancing the movable tape.

5. In a registering apparatus, a wheel mounted for rotation, type carrying plungers arranged radially of said wheel, a hammer device in position to engage said plungers as they are moved into operative position relative thereto, a recording strip movable relative to said wheel and adapted 95 to consecutively receive an imprint from the plungers, a ratchet rotatable with the wheel and having teeth corresponding to the plungers thereof, a spring controlled member movable relative to said ratchet, an operating pawl pivoted to said spring controlled member and engageable with the teeth of said ratchet, a backing pawl engageable with the teeth of said ratchet, electrically operated means for said operating pawl 100 and electrically operated means for actuating said hammer device.

In testimony whereof, I affix my signature hereto.

LAURENCE D. HARRISON.
